UNITED STATES PATENT OFFICE.

AUGUST B. BECK, OF JERSEY CITY, NEW JERSEY.

DESIGN FOR A LADY'S GIRDLE.

58,987.

Specification for Design.

Patented Sept. 13, 1921.

Application filed March 7, 1921. Serial No. 450,489. Term of patent 14 years.

To all whom it may concern:

Be it known that I, AUGUST B. BECK, a citizen of the United States, residing at Jersey City, in the county of Hudson and State of New Jersey, have invented a new, original, and ornamental Design for a Lady's Girdle, of which the following is a specification, reference being had to the accompanying drawing, forming part thereof.

Figures 1 and 2 are perspective views of a girdle showing the design and looking respectively at the front and rear of the girdle.

I claim:

The ornamental design for a lady's girdle as shown.

AUGUST B. BECK.
